STOKER

Eugene Martin, Erie, Pa., assignor, by mesne assignments, to The Standard Stoker Company, Inc., New York, N. Y., a corporation of Delaware

Application July 20, 1934, Serial No. 736,203

7 Claims. (Cl. 110—101)

This invention relates to stokers for locomotives or other steam generating devices and it appertains particularly to stokers of the character disclosed in the United States Letters Patent No. 5,1947,723, granted February 20, 1934, to Nathan M. Lower.

M. Lower.

It is accordingly the main object of the invention to provide a stoker of the aforesaid character in which the chambered floor portion, known in the trade as the jet plate, of the discharge conduit is formed separate from the conduit and secured thereto by fastening members engaging the conduit and upstanding flanged extensions of the jet plate. More specifically the invention contemplates extending the chambers of the body portion of the jet plate into the flanged extensions which are apertured for the introduction of pressure fluid to the chambers.

Another object of the invention is the provision of a stoker discharge conduit and a separable chambered jet plate arranged with the chambered portion of the main body thereof positioned approximately within the confines of the firing opening of the firebox.

25 Other objects reside in the particular construction of the jet plate and the discharge conduit as individual parts; in their arrangement one with the other; and in the relation of the fuel deflectors to the discharge conduit and to the jet plate, as hereinafter fully described and as shown on the accompanying drawings, in which,

Figure 1 is a detail vertical section through the upright wall of a boiler firebox showing the device of the invention applied thereto in similar section;

35 Figure 2 is a fragmentary sectional view taken on the line 2—2 of Figure 1;

Figure 3 is a fragmentary vertical elevation of the structure shown in Figure 1 considered on the line 3—3 thereof;

40 Figure 4 is a front elevation of the jet plate embodied in the device of the invention;

Figure 5 is a plan view of the jet plate with portions shown in section on the line 5-5 of Figure 4 and with other portions broken away;

45 Figure 6 also is a plan view of the jet plate but with some portions shown in section taken on the line 6-6 of Figure 4 and with other portions broken away; and

50 Figure 7 is a view similar to Figures 5 and 6 but with a portion of the jet plate shown in section on the line 7-7 of Figure 4 and with other portions broken away.

Throughout the following description and the claims it will be understood that such terms as

"rearward" or "forward" or equivalent expressions are employed with respect to the direction of flow of fuel to the firebox.

Referring to the drawings, there is shown at 10 a portion of an upstanding wall or backhead of a boiler firebox having a firing opening 11 therein to which fuel is advanced by the screw 12 housed within the inclined stoker discharge conduit 13 which opens endwise into the firing opening. Rearward of the conduit 13 and universally connected thereto there is disposed the rearwardly extending conduit section 14, which may be of any well known construction, leading rearwardly to a source of fuel supply from which the fuel is carried forwardly by a screw conveyor 12a into the discharge conduit 13 through which it is advanced by the screw 12. The mouth portion 15 of the discharge conduit flares laterally, as best shown in Figure 2, and carries the laterally extending flanges 16, 17 arranged in spaced relation with the backhead 10 and which at their remote ends turn rearwardly forming the longitudinally extending flanges 16a, 17a for attachment respectively to the brackets 18 and 19 which may be secured to the boiler backhead 10 in any desired manner to support the upper end portion of the conduit 13. Bolts as at 20 secure the conduit to the brackets. The lower end of conduit 13 also is supported from the boiler backhead 10 by a bracket 21 which is provided with a seat 22 for receiving the foot member 23 of the conduit. In this manner the discharge conduit 13 is rigidly mounted with the boiler backhead.

Preferably, the bottom wall or floor 24 and the side walls 25, 26 of the conduit at their forward ends terminate in substantially the same transversely extending vertical plane at a point rearward of but closely adjacent the backhead 10 opposite the firing opening 11. This greatly facilitates machining operations of the conduit and associated parts.

A jet plate 27 is mounted at the forward end of the conduit 13 to form a continuation of the bottom wall 24 extending from the upper end of the latter into the firing opening 11 where the jet plate is formed with the transversely extending upstanding front face 28 having jet openings as at 29 for the discharge of pressure fluid over and above the forwardly extending distributing table 30. This table may be supported from the jet plate in any suitable manner and its construction and relation with the jet plate is of well known construction forming no part of the present invention and therefore will not be further described. 45 50 55

Rearward of the face 28 the jet plate includes a broad flat floor portion 31 extending the full width of the conduit mouth portion 15 to form, in effect, an extension or continuation of the floor 5 24 thereof. At opposite sides of the floor 31 the jet plate is provided with upstanding rearwardly extending oppositely spaced flanged extensions 32, 33 for attachment to the flanges 16, 17 of the discharge conduit 13. Fastening members such as 10 the bolts 34 secure the flanged extensions and thereby the jet plate to the aforesaid flanges of the conduit and thus maintain the jet plate in proper relation with the conduit floor 24. It will be observed the flanged extensions 32, 33 are 15 spaced at the sides of the discharge mouth 15 and do not interfere with the movement of the fuel over the floor portion 31 onto the distributor table 30.

Pressure fluid is conducted to the openings 29 20 by a plurality of chambers in the jet plate. These chambers are best illustrated in Figures 1, and 4 to 7 inclusive. Referring to these figures and particularly to Figures 1, 4 and 5, it will be seen that the sidewardly directed jets 29a, 29b 25 are supplied with pressure fluid respectively from the chambers 35, 36, which chambers extend from the jet openings in the front face 28 of the jet plate rearwardly through the body portion of the plate into a respective flanged extension. From Figures 1 and 5 it will be noted that the chamber 35 extends into the flanged extension 32 apertured as at 37 for the introduction of pressure fluid to the chamber. Likewise, from these figures it will be observed that 35 the chamber 36, which supplies pressure fluid to the jet openings 29b, extends rearwardly and upwardly into the flanged extension 33 apertured as at 37a for the introduction of pressure fluid to this chamber.

40 Supply pipes 37b and 37c, extending respectively through the elongated slots 38, 38a in the flanges 16 and 17 of the conduit, communicate respectively with the apertures 37a and 37 for supplying pressure fluid to the chambers 36 and 45 35 and hence to the jet apertures 29b and 29a.

Similarly, the jet openings 29c, spaced in a horizontal row across the lower portion of the jet face 28 in a position to project over the table 30, are supplied with pressure fluid from the 50 single chamber 39, as best shown in Figures 1, 4 and 7. This chamber extends rearwardly to the lower portion of the flanged extension 33 apertured at 39a to receive a supply pipe 39b through the slot 38 for the introduction of pressure fluid to the chamber 39.

Above the jet openings 29c are disposed two horizontal rows of jet openings divided centrally into the groups 29d and 29e. The jet openings 29d communicate with the chamber 40, which, 60 as best shown in Figures 1, 4 and 6, extends rearwardly through the body portion of the jet plate into the flanged extension 32 apertured at 40a to receive the supply line 40b extending through the slot 38a for supplying pressure fluid 65 to the chamber 40 and hence to the jet apertures 29d. Similarly, the group of jet openings 29e communicates with a chamber 41 extending through the body portion of the jet plate into the flanged extension 33 apertured at 41a 70 to receive the supply line 41b projecting through the slot 38 for introducing pressure fluid to the chamber 41 and hence to the group of jet openings 29e. The invention contemplates that each 75 of the aforesaid supply lines will be provided with control valves (not shown) operable inde-

pendently of one another for independent regulation of the pressure fluid to the different groups of jet openings for attaining, in cooperation with the distributing table 30, even distribution of the fuel over the grates 45 of the firebox 46.

This construction of the jet plate makes a compact arrangement of the chambers under its floor 31 and within the confines of the firing opening; and by extending these chambers laterally and then rearwardly and upwardly into the flanged extensions 32 and 33 instead of rearwardly along and beneath the floor 31 to the rearward end thereof, it is possible to place the floor 24 of the conduit 13 and the floor 31 of the jet plate closer to the lower marginal edge 15 of the firing opening 11 and thus occupy less vertical space in the firing opening and permit the use of a smaller angle of inclination of the discharge conduit with the horizontal. This is particularly advantageous on locomotives where 20 it is desirable to reduce the space occupied by the discharge conduit in the locomotive cab which, in the drawings at Figure 1 is indicated at 47 and the cab floor at 48.

In a stoker of this character, the screw 12 25 delivers to the discharge mouth 15 by the direct action of its impelling flights. Consequently, there is a tendency for the fuel to be discharged more to one side of the discharge mouth 15 than the other. This is overcome and even deflection of the fuel to the distributing table is provided by the oppositely disposed upstanding fuel deflectors 50, 51 which are pivoted respectively at 50a, 51a in the conduit 13 adjacent respective side walls thereof and rearward of 35 the jet plate 27. The axes of the pivots 50a, 51a are disposed substantially perpendicular to the flow of fuel through the discharge conduit so that by swinging the deflectors 50, 51 about their axes the fuel may be deflected laterally to one 40 side of the jet plate or the other as desired. In effect, the fuel deflectors constitute an expandable and contractible extended mouth portion of the discharge conduit. It will be observed the deflectors extend beyond the side walls of the 45 conduit forwardly to a point adjacent the front face 28 of the jet plate 27 and that they are spaced between the flanged extensions 32, 33 of the jet plate to guide the fuel forwardly over the jet plate floor 31 into the zone of action of the 50 pressure fluid blasts sweeping across the distributing table 30.

Adjusting screws 55, 56 extending substantially parallel to the backhead 10 pass through lugs on the flanges 16a, 17a and are threaded into the conduit side walls 25, 26 forward of the pivots 50a, 51a to contact the deflectors 50, 51 for moving them inwardly of the conduit. The deflectors may be permitted to move outwardly of the conduit by withdrawing the adjusting screws 55, 56 60 to the extent desired and the pressure of the fuel will spread the deflectors until stopped by contact with the adjusting screws.

Those familiar with the art will recognize this invention provides a very compact arrangement 65 between the jet plate and the stoker discharge conduit whereby a minimum of space is occupied in the firing opening while, at the same time, the pressure fluid supply lines to the chambers of the jet plate are readily accessible and convenient 70 for making replacements or repairs as well as being convenient for removal to clean out the chambers or the jet openings or, when desired, to remove the jet plate.

I claim:

1. In a stoker, the combination of a conduit and a jet plate disposed at the delivery end thereof, said conduit having bottom and side walls terminating at the delivery end of the conduit in substantially the same transverse vertical plane and including flanges extending laterally from said side walls in the aforesaid plane, the jet plate having a floor constituting a continuation of the bottom wall of the conduit and including flanged extensions at the sides of and extending above said floor disposed against the flanges of the conduit, and fastening members securing the flanged extensions of the jet plate to said flanges of the conduit, said jet plate including chambers adapted to receive pressure fluid, such chambers having jet openings arranged to discharge therefrom.

2. In a stoker, the combination of a conduit and a jet plate disposed at the delivery end thereof, said conduit having bottom and side walls terminating at the delivery end of the conduit in substantially the same transverse vertical plane and including flanges extending laterally from said side walls in the aforesaid plane, the jet plate having a floor constituting a continuation of the bottom wall of the conduit and including flanged extensions at the sides of and extending above said floor disposed against the flanges of the conduit, and fastening members securing the flanged extensions of the jet plate to said flanges of the conduit, said jet plate including chambers underneath its floor extending into said flanged extensions, said flanged extensions having apertures for the introduction of pressure fluid to the chambers and said jet plate being provided with jet openings communicating with the chambers for the discharge of pressure fluid therefrom.

3. In a stoker, in combination, a conduit, a jet plate disposed at the delivery end thereof, said conduit having bottom and side walls terminating at the delivery end of the conduit in substantially the same transverse vertical plane, a flange extending laterally at the aforesaid end of the conduit at each side wall thereof and disposed in the aforesaid plane, said jet plate having a floor constituting a continuation of the bottom wall of the conduit and said jet plate including a pair of spaced flanged extensions one positioned at each side of and extending above said floor and each disposed against a respective flange of the conduit, and fastening members securing the flanged extensions of the jet plate to said flanges of the conduit, said jet plate including a plurality of separated chambers underneath its floor arranged with one of said chambers extending into one of said flanged extensions and another of said chambers extending into the other flanged extension, said extensions having apertures for the introduction of pressure fluid to the chambers and said jet plate including jet openings communicating with the chambers for the discharge of pressure fluid therefrom.

4. In a stoker, in combination, a conduit, a jet plate disposed at the delivery end thereof, said conduit having bottom and side walls terminating at the delivery end of the conduit in substantially the same transverse vertical plane, a flange extending laterally at the aforesaid end of the conduit at each side wall thereof and disposed in the aforesaid plane, said jet plate having a floor constituting a continuation of the bottom wall of the conduit and said jet plate including a pair of spaced flanged extensions one positioned at each side of and extending above said floor and each disposed against a respective flange of the conduit, and fastening members securing the flanged extensions of the jet plate to said flanges of the conduit, said jet plate including a plurality of separated chambers underneath its floor arranged with one of said chambers extending into one of said flanged extensions and another of said chambers extending into the other flanged extension, said extensions having apertures for the introduction of pressure fluid to the chambers and said jet plate including jet openings communicating with the chambers for the discharge of pressure fluid therefrom.

5. As an article of manufacture, a stoker jet plate when in an operative position including a floor constituting a fuel supporting surface, said jet plate being provided with a plurality of chambers for receiving pressure fluid, and a pair of extensions rising above the level of said floor, one at each side thereof, to form a means whereby said jet plate is secured in its operative position, said extensions being provided with passages communicating with said chambers, said passages having rearwardly opening pressure fluid intake openings in the rearward side of said extensions, the aforesaid rearward sides of the extensions terminating in the same approximately vertical plane.

6. In a stoker, the combination of a conduit and a jet plate disposed at the delivery end thereof, said conduit having bottom and side walls, and a flange extending laterally from each side wall, the jet plate having a floor constituting a continuation of the bottom wall of said conduit and including flanged extensions at the sides of and extending above said floor and being disposed against the flanges of the conduit, and fastening members securing the flanged extensions of the jet plate to the flanges of said conduit, said jet plate including chambers underneath its floor extending into said flanged extensions, said flanged extensions having apertures for the introduction of pressure fluid to the chambers and said jet plate being provided with jet openings communicating with the chambers for the discharge of pressure fluid therefrom.

7. In a stoker, the combination of a conduit and a jet plate disposed at the delivery end thereof, said conduit having bottom and side walls, and a flange extending laterally from each side wall, the jet plate having a floor constituting a continuation of the bottom wall of said conduit and including a pair of flanged extensions one positioned at each side of and extending above said floor and each being disposed against a respective flange of said conduit, and fastening members securing the flanged extensions of the jet plate to the flanges of said conduit, said jet plate including a plurality of separated chambers underneath its floor arranged with one of said chambers extending into one of said flanged extensions and another of said chambers extending into the other flanged extension, said extensions having apertures for the introduction of pressure fluid to the chambers and said jet plate including jet openings communicating with the chambers for the discharge of pressure fluid therefrom.

EUGENE MARTIN.
